33 shall not be considered as original, or patentable, in respect to the invention described and claimed in this application.

UNITED STATES PATENT OFFICE.

34 Issued under the laws of the United States of America, and in the name of the United States of America.

35 **OLIVER C. RITZ-WOLLER, OF CHICAGO, ILLINOIS.**

36 **LOCK FOR RECEPTACLE-CLOSURES.**

37 **1,096,951.**

38 **Specification of Letters Patent. Patented May 19, 1914.**

39 **Application filed May 21, 1913. Serial No. 769,107.**

40 *To all whom it may concern:*

41 Be it known that I, OLIVER C. RITZ-WOLLER, citizen of the United States, residing at Chicago, in the county of Cook and State of Illinois, have invented certain new and useful Improvements in Locks for Receptacle-Closures, of which the following is a specification, reference being had to the accompanying drawings.

42 This invention relates to improvements in locks for receptacle closures, and has for its primary object to provide a simple and efficient device for locking caps upon automobile radiators, fuel storage tanks and in all other instances where a device of this character may be found desirable.

43 The invention has for another and more specific object the provision of a cap or closure for the filling opening of the tank or reservoir which is provided with an annular series of rack teeth, and a lock secured upon the tubular filling nipple or extension of the tank or reservoir including a spring pressed locking bolt to engage the annular series of rack teeth when the cap is threaded to its closed position and prevent reverse movement of the cap.

44 The invention has for a further object the provision of improved means for attaching the lock to the filling nipple.

45 With the above and other objects in view as will become apparent as the description proceeds, the invention consists in certain constructions, combinations and arrangements of the parts that I shall hereinafter fully describe and claim.

46 For a full understanding of the invention, reference is to be had to the following description and accompanying drawings, in which—

47 Figure 1 is a side elevation showing a cap locked upon the filling nipple of an automobile radiator by means of the present invention; Fig. 2 is a section taken on the line 2—2 of Fig. 1; Fig. 3 is a section taken on the line 3—3 of Fig. 1.

48 Referring in detail to the drawing, 5 designates a portion of an automobile radiator, although it is to be understood that the present invention is applicable as well to gasoline storage tanks and other receptacles. The tank or radiator is provided with the usual filling extension or nipple 6, having a reduced exteriorly threaded upper end 7. The closure cap 8 for the filling nipple may be of any preferred form and includes a

body which is reduced in thickness at its edge to form an annular flange 9 and a shoulder 10 at the inner end of said flange. This shoulder is provided with teeth 11 facing in a direction opposite to that in which the cap is turned when it is threaded to its closed position upon the nipple 6.

49 A flexible metal band 12 surrounds the nipple 6 adjacent the threaded portion 7 thereof and at one of its ends is fastened by means of a screw 13 to said nipple. The lock casing 14 is provided upon opposite ends with the loops 15 through which the extremities of the metal band 12 are disposed. One end of the band is returned upon itself after being passed through one of the loops 15 and inserted through a metal loop 16 arranged upon the band. This loop 16 is held against shifting movement by means of the screws 17 which have threaded engagement in openings provided in the band. These screws are arranged upon opposite sides of the loop 16. Thus the end of the band will be effectually retained in connection with the loop 15 on the lock casing 14. The lock casing 14 is preferably of rectangular form and within the same, a locking bolt 18 is arranged, said bolt being movable through an opening in the upper wall of the lock casing and between one of the end walls thereof and a guide plate 19. The inner lower end of this locking bolt has a lug 20 formed thereon, and a coil spring 21 is arranged in the casing and bears against the lower end of the locking bolt to normally force the same upwardly.

50 22 designates an opening in the front wall of the lock casing to receive a suitable key, which when turned engages the lug 20 of the locking bolt as shown in dotted lines in Fig. 1 to force said bolt downwardly and release the cap so it can be removed from the filling nipple or extension of the tank or reservoir.

51 From the above description, the operation of the invention will be obvious. As the closure cap 8 is threaded downwardly upon the upper end of the filling nipple, the annular series of rack teeth 11 thereof engage the upper end of the locking bolt 18 and ride over the same, said bolt being gradually forced downwardly against the action of the spring 21. It will thus be apparent that when the cap has been threaded to its closed position, the end of the bolt bearing against one of the teeth 11 will effectually prevent

any reverse turning movement of the cap so that it cannot be removed from the nipple. Unauthorized persons are therefore prevented from obtaining access to the interior of the tank or reservoir while at the same time, the cap may be readily removed by the possessor of the key. After inserting the key through the opening 22 of the lock casing, it is only necessary to turn the same to cause the wing or flange of the key to bear against the lug 20 and force the locking bolt downwardly to its release position whereby the closure cap may be easily and quickly unthreaded and removed from the upper end of the nipple 6.

From the foregoing, it is thought that the construction and operation of the invention will be clearly understood. It will be understood that by providing the band 12 for attaching the lock casing to the filling extension or nipple of the tank or reservoir, it is only necessary to secure said band to the wall of the nipple at one of its ends, the other end of the band being connected to the lock casing in the manner above described. It will however, be appreciated that instead of employing this band, the lock casing might be otherwise attached to the

filling nipple or extension of the tank if desired. It will further be obvious that my invention is capable of many minor modifications in the form, proportion and arrangement of the several elements employed without departing from the essential features thereof or sacrificing any of the advantages of the device as claimed.

Having thus described the invention, what is claimed is:

The combination with a tank or reservoir having a filling nipple, of a closure cap for said nipple provided with an annular series of rack teeth, and an annular flange on said rack teeth, and a lock secured upon the filling nipple including a locking bolt adapted to extend between the flange of the cap and the nipple and engage with said rack teeth, when the cap is threaded to its closed position to prevent reverse turning movement of the cap.

In testimony whereof I hereunto affix my signature in the presence of two witnesses.

OLIVER C. RITZ-WOLLER.
